Primary Examiner — Michael A Maharajh(74) *Attorney, Agent, or Firm* — Polson Intellectual Property Law, PC; Margaret Polson(57) **CLAIM**

The ornamental design for cardio equipment, as shown and described.

DESCRIPTION

FIG. 1 is a front perspective view of cardio equipment;

FIG. 2 is a front view of FIG. 1;

FIG. 3 is a back view of FIG. 1;

FIG. 4 is a left-side view of FIG. 1;

FIG. 5 is a right-side view of FIG. 1;

FIG. 6 is a top view of FIG. 1; and,

FIG. 7 is a bottom view of FIG. 1.

The broken lines in the drawings are for the purposes of illustrating environmental structure, which form no part of the claimed design.

1 Claim, 7 Drawing Sheets(56)
